UNITED STATES PATENT OFFICE.

OTTO JOHNE, OF BAUTZEN, GERMANY.

INKING APPARATUS FOR PLATEN PRESSES.

Application filed November 25, 1924. Serial No. 752,226.

To all whom it may concern:

Be it known that I, OTTO JOHNE, a citizen of Germany, residing at Bautzen, Germany, have invented new and useful Improvements in Inking Apparatus for Platen Presses, of which the following is a specification.

This invention relates to platen presses with inking mechanism composed of rollers. In machines of this type, which have been used hitherto, the inking rollers circulate around the base plate or return idle over the same so that the rollers are continuously in movement and come in contact with the ink cylinder only for a very short time for taking and spreading ink. In other machines of similar type the rollers move over the platen once downwardly and then upwardly. In this case complete inking mechanisms each consisting of an ink box, an ink box cylinder, spreading rollers and inking rollers, are arranged one above and the other below the machine. An inconvenience resulting from this arrangement is that the inking of the inking rollers above the machine is different from the inking below the machine when the inking mechanisms are not adjusted quite uniformly. In some machines of known type the inking rollers are of comparatively small diameter so that they rotate on the form several times, wherefrom an irregular inking of the form results.

According to the invention the length of the circumference of the inking rollers is at least equal to the height of the type form. They are conducted over the form alternatingly once from the lower end to the upper end and then from the upper end to the lower end, so that, prior to each printing operation, they rotate once slowly on the form. One inking apparatus is arranged, divided into two parts, on the platen press in such a manner that one large inking roller is situated above and another one below the form. The ink is supplied to these two inking rollers from one and the same ink box. The ink is transmitted from the ink box cylinder to the distributing rollers by means of two elevator cylinders which deliver ink alternately to the distributing

roller arranged above the form and to the distributing roller arranged below the form.

An embodiment of the invention is diagrammatically shown, by way of example, in the figure of the accompanying drawing. 55

The inking rollers 1 and 2 are moved along the form, by convenient mechanisms known per se, downwardly and then upwardly after every printing operation of the platen 17. Above and below the form 3 ink cylinders 4 and 5 are arranged to which the ink is supplied from the ink box cylinder 8 through the intermediary of the elevator cylinders 6 and 7 by the distributing rollers 9, 11, 13, 15 and 10, 12, 14, 16. 65 The elevator cylinders 6 and 7 are alternatingly brought in contact with the ink box cylinder 8. During the printing operation the inking rollers 1 and 2 are either in contact with the ink cylinder 4 above the 70 form or with the ink cylinder 5 below the form.

The platen is operated as usual from the driving shaft 18 by means of toothed wheel 19 and connecting rod 20. 75

I claim:

1. An inking apparatus for platen presses comprising in combination an ink cylinder above the form of the press, an ink cylinder below the form, and two inking rollers oscillating between said two ink cylinders in such a manner that they roll prior to every printing operation once over the form and ink the same completely by one single rotation. 85

2. An inking apparatus for platen presses comprising in combination an ink cylinder above the form of the press, an ink cylinder below the form, two inking rollers oscillating between said two ink cylinders, in such a manner that they roll prior to every printing operation once over the form and ink the same completely by one single rotation, one ink box and one ink box cylinder for the two ink cylinders. 95

3. An inking apparatus for platen presses comprising in combination an ink cylinder above the form of the press, an ink cylinder below the form, two inking rollers oscillating between said two ink cylinders in such 100

a manner that they roll prior to every printing operation once over the form and ink the same completely by one single rotation, an ink distributing roller above the 5 form, an ink distributing roller below the form, an ink box and an ink box roller for the two ink distributing rollers and two ele-

vator cylinders for supplying ink alternately to the one and to the other distributing roller.

10

In testimony whereof, I have signed my name to this specification.

OTTO JOHNE.
